Inventor

A. J. Gregory.

By William J. Jaschinski

Attorney

UNITED STATES PATENT OFFICE.

ADOLPH J. GREGORY, OF DENBIGH, NORTH DAKOTA.

BUTTON.

Application filed February 17, 1922. Serial No. 537,176.

To all whom it may concern:

Be it known that ADOLPH J. GREGORY, a citizen of the United States, residing at Denbigh, in the county of McHenry and State of North Dakota, has invented certain new and useful Improvements in Buttons, of which the following is a specification.

This invention relates to buttons and particularly to separable buttons of a type wherein the head or body of the button is separable from its attaching means to permit its ready application and removal with respect to the garment with which it is to be associated.

One of the particular features of my invention resides in a button, the head of which is recessed to receive a clamping device applied to the end of the screw and which cooperates with the button to attach it to the garment or other fabric.

While I am aware of the fact that separable buttons have been heretofore manufactured, those with which I am familiar have been to a large extent more or less complicated in structure, and in a number of instances were so constructed that they would easily be pulled apart when subjected to abnormal pressure while others when once assembled could not readily be taken apart except by undue exertion.

My invention is directed toward a separable button which when once applied cannot accidentally come apart, but which may by the application of a simple tool be disassembled and reused as often as necessary and practically indefinitely in view of the fact that the parts are of sturdy construction and not liable to break.

Further, the particular locking device for the button attaching means is so arranged that it is neither unsightly nor in a position to interfere with the application of the button through the button-hole, being disposed within a recess in the button face, which latter therefore remains free and unobstructed.

In the accompanying drawings which illustrate preferred embodiments of my invention,

Figure 1 is a top plan view of my separable button;

Figure 2 is a side elevation thereof;

Figure 3 is a vertical sectional view of the button on the line 3-3 of Figure 1;

Figure 4 is an end view of a cuff button of a separable screw type;

Figure 5 is a bottom plan view of a collar button of the separable screw type;

Figure 6 is a side elevation of the type 60 of cuff button shown in Figure 4, the screw connection being shown in section; and

Figure 7 is a side elevation of the type 65 of collar button shown in Figure 5, the screw connection being shown in section.

Referring now more particularly to the several figures of the drawing by numerals of reference, 2 indicates generally a button, the body of which I prefer to construct in the form of a metal shell comprising a base 70 portion 4, and a top member 6, spaced apart and joined at their peripheries at the point 8 defining thereby a recess 10.

The base portion 4 is provided with a depending centrally located stud or shank 12, 75 while the top member 6 is provided with a central and preferably circular aperture 14 to permit access to the interior of the shell for purposes to be presently described.

For the purpose of separably attaching 80 the button to a garment or other fabric 16, I provide the stud or shank 12 with an axial threaded opening to receive the threaded stem 18 of a screw, the peripherally knurled head 20 of which is smooth on its inner face and cooperates with the smooth opposed face of the stud or shank to grip the fabric 16 when the screw is turned home, the end of the screw being pointed as at 22 to enable it to puncture or penetrate the fabric. 85

To the end that the button and the attaching screw may not be relatively rotatable or displaced, I provide a locking means for the screw, this comprising a nut 24 preferably of the wing type which is 95 threaded on the free end of the screw 18, being inserted through the aperture 14 provided for the purpose. The recess 10 therefore securely houses the nut 24 which after being screwed home is free of contact with 100 anything which might tend to loosen or displace it. Furthermore, by constructing the body of the button in the form of a shell, the article is materially lightened in weight and the cost of material considerably reduced.

In Figures 4 and 6 I have illustrated in end and side elevation, a separable cuff button 40, the link 42 of which is formed in two sections, the adjoining ends of which 110

are provided respectively with a screw and threaded socket connection 46.

In Figures 5 and 7 I have shown a separable collar button 48, the shank 50 of 5 which is formed in two sections, and joined by a screw and socket connection 52 as in the case of the cuff button.

Having thus described my invention, what I claim as new and desire to protect 10 by Letters Patent is:

1. A separable button of the character described, comprising a button member provided with a facial recess, a stud formed integral with and depending from the bottom face of said button and provided with an axial threaded bore, a fastening member for said button comprising a screw adapted to pass through said threaded bore and having an external operating head, and a 20 lock nut secured on the inner end of said screw and disposed wholly within said recess.

2. A separable button of the character

described, comprising a button body member having spaced top and bottom plates secured together at their peripheral edges to provide a hollow structure, said upper plate being provided with a central opening communicating with the interior of said button body member, a stud depending from the lower face of said bottom plate and having an axially threaded bore, a button attaching screw adapted to pass through said threaded bore and extend into the interior of said hollow button, a locking wing-nut 35 adapted to be passed through the central opening in said top plate and be secured on the inner end of said screw, said nut being wholly disposed within the hollow body of 40 said button, and said screw having an enlarged operating and garment clamping head cooperating with the outer face of said stud.

In testimony whereof I affix my signature.

ADOLPH J. GREGORY.
